UNITED STATES PATENT OFFICE

JESSE E. MATEER, OF WILKINSBURG, PENNSYLVANIA, ASSIGNOR TO WESTINGHOUSE ELECTRIC & MANUFACTURING COMPANY, A CORPORATION OF PENNSYLVANIA

HIGH-VOLTAGE STRUCTURE

Application filed May 19, 1927. Serial No. 192,589.

My invention relates to high-voltage structures and particularly to bushing structures and the associated parts of oil filled circuit interrupters, or similar devices, with which the bushings are associated.

One object of my invention is to provide a structure of the above-indicated character that shall permit the bushing, as one unit, and a main casing or tank, a well structure 10 for local disposition about a portion of the bushing in the tank, and other parts, as another unit, to be adjusted relatively at, and shipped separately from, the factory and assembled at the service station, without further 15 adjustment.

Another object of my invention is to provide a bushing structure, for a high-voltage, oil-filled circuit interrupter, in which a body of oil, immediately adjacent to the bushing, 20 shall be maintained free of carbon and metallic particles which are given off to the main oil body when the interrupter operates under heavy loads.

Another object of my invention is to provide a well structure, for local disposition 25 about the inner end of a circuit-interrupter or similar bushing, that shall be adapted for insertion through the bushing opening in the interrupter tank and that shall permit the 30 mounting of the bushing and of the well structure from the outside of the tank.

Another object of my invention is to provide a well structure, for the reception of a bushing, in which a flexible conductor, for 35 threading through the bushing, shall be mounted for shipping with the well, separately from the bushing, and so fixed or adjusted at the factory as to require no further adjusting and to prevent its loosening by the 40 effects of current therein.

Another object of my invention is to provide an effectively sealed bushing structure that shall embody means for adjusting a conductor or contact member, at one end thereof, 45 relative to a cooperating conductor adjacent to said end, as by bodily adjusting the bushing relative to a wall or cover member with which it is associated.

Another object of my invention is to provide a bushing structure that shall so embody

a condenser bushing and a surrounding well or oil contained therefor as to withstand very high voltages and to be, in general, an improvement over bushing structures heretofore employed.

Another object of my invention is to provide a well structure, for a high-voltage bushing, that shall comprise a metal section and a relatively massive oil-immersed porcelain section having a creepage surface of relatively great area, that shall be adapted for the reception of a transformer element and that shall embody effectively sealed terminals for the transformer element.

A further object of my invention is to provide a high-voltage structure that shall be simple and durable in construction, economical to manufacture and effective in its operation.

In high-voltage structures, such as oil-filled 70 circuit interrupters, the various parts must be exceedingly carefully designed, constructed, assembled, and adjusted because of the high-voltage stresses, the presence of oil, the formation of gases and arcs, and other features.

Care must be taken, not only from a safety standpoint, but also that the device may always be in condition, when required to operate to a maximum degree of efficiency and not 80 be rendered ineffective from preceding operations.

Since, in oil-filled circuit interrupters, the inner ends of the terminal bushings are usually immersed in the same body of oil that surrounds the contact members, carbon and metallic particles, which are sometimes formed when the interrupter operates under heavy loads, reduce the insulating value of the oil and tend to break down the surface of the 90 bushing therein. The inner ends of such bushings are, also, usually provided with limited or insufficient creepage surface. Also, by reason of their size, certain of these interrupters and the bushings therefor are 95 shipped separately and assembled at the place of installation.

Since the parts must be carefully put together at the factory, considerable trouble and expense are occasioned by the delicate 100

adjustments which must be twice performed, where the interrupters and bushings are assembled at the factory, disassembled, shipped and again assembled.

Further, there is the danger that the second, or final, assembly may not be so carefully performed as the first assembly, with the consequent less effective operation and greater likelihood of damage.

It is my aim to reduce the above-mentioned effect of the carbon and metallic particles in structure of their character to employ a condenser bushing that shall be entirely free of such particles, to provide a device having materially increased creepage-surface area, and to provide a structure in which the field mounting of the bushings shall be free of delicate adjustments and thereby rendered a simple and economical operation.

Accordingly, in practicing my invention, I provide a well structure for local disposition about the inner end of a bushing, that functions as a barrier between the oil next to the bushing and the main body of oil in an interrupter tank. The well structure and a flexible conductor, for threading through the bushing, are so assembled and adjusted relative to the tank and a movable contact member therein, and the bushing is so adapted for mounting in the well, as to permit the ready and economical mounting of the bushing during the installation of the interrupter, without delicate adjustment or the requirement of special skill. The arrangement of parts is so improved as to provide a materially increased creepage surface compared to structures heretofore employed.

Figure 1 of the accompanying drawings is a view, partially in section and partially in elevation, of a high-voltage structure embodying my invention, and

Fig. 2 is a similar view of a modified form thereof.

Referring to Fig. 1, the device comprises, in general, a wall or cover member 2 of a tank or casing (not shown), a well structure 4, a current-transformer element 5 in the well 4, and a condenser-bushing structure 6.

The cover member 2, preferably constructed of metal, is provided with a bushing opening 7 and an annular flange 9 is provided with an inwardly-sloping or beveled outer end edge.

The well structure 4 comprises an upper or open-end metal section 12, a lower or bottom insulating section 14, a top cover member 15 and a bottom structure 16.

The metal section 12, preferably of relatively thin-walled uniform cylindrical shape, comprises a laterally, outwardly-projecting upper flange 18, an inwardly-projecting lower flange 19 and a downwardly projecting lower flange 20.

The upper flange 18 embodies a sloping under surface 22 that so cooperates with the

sloping outer surface of the flange 9, through a gasket 23, as to permit an adjustment of the well to be hereinafter set forth.

The flange 18 further comprises a downwardly-projecting strengthening-and-positioning rib 25 and a portion 26. Bolts 27 extend between the portion 26 of the flange 18 and bosses 28 on the cover 2 to hold the well 4 in adjusted position.

The well cover 15, which rests on a sealing gasket 30 disposed over the top edge of the sections 12, has an opening 31, a flange 32 about the opening 31, and an outwardly-and-downwardly extending outer-edge portion 33. Bolts 34 extend through the portion 33 and into the flange 18 for securing the well cover 15 in sealed position.

The lower inwardly-projecting flange 19 provides a seat for the transformer element 5 and an end shoulder for the upper end of the insulating section 14.

The downwardly-projecting lower flange 20 is constructed to have an inner diameter substantially equal to the outer diameter of the main body portions thereof and to relatively closely embrace a portion of the upper end of the insulating section 14.

A sealing and securing medium, preferably of rubber compound, is placed between the flanges 19 and 20 and the adjacent surfaces of the section 14.

The insulating section 14 is preferably of relatively thick-walled and massive porcelain construction, the side wall 35 of which converges downwardly and is provided with surface-creepage flanges 36.

Since all of the well structure 4, beneath the flange 18, is adapted for insertion through the opening 7 in the cover 2, the top flange 36 is of smaller diameter than the opening 7 and projects only a certain distance from the main wall 35 of the section 14. However, by reason of the downwardly-converging or tapering form of the wall 35, the flanges 36, under the top flange thereof, may extend farther from the wall and are preferably of uniformly increasing distances therefrom. This arrangement provides surface-creepage distances that are greater near the position of higher voltage gradient and that gradually decrease therefrom.

The bottom structure 16 comprises a collar or sleeve portion 39 that is secured, as by a body of cement 40, around the lower end of the wall 35 and has a bottom surface that is preferably flush with the bottom surface of the wall 35.

A metal plate 42, disposed flatly across the bottom end of the section 14, is sealed and secured thereto, as by a gasket 43 and screws 44, respectively.

A screw-threaded conducting stud element 46, which may be integral with or otherwise suitably secured to the plate 42, projects from the plate for the reception of a stationary con-

tact structure (not shown) of the interrupter and has an opening at the inside of the plate for the reception of one end of a flexible conductor or cable 48 which extends through the bushing 6. The cable 48, stud, 46, and plate 42 are permanently connected to each other, as by welding, to resist the highest mechanical and electrical stresses which are ordinarily met with in service, without impairing the connection.

The current-transformer element 5, of which the cable 48 constitutes a one-turn primary winding, comprises a laminated ring core member 50 and a secondary or low-voltage winding 51 which closely conforms to the inner diameter of the section 12 and is supported by the flange 19.

An oil-tight, low-voltage terminal device for the transformer 5 comprises an insulating bushing 53, extending through the wall of the well section 12, a conductor 54, extending through the bushing, washers 55 and nuts 57 for attaching adjacent conductors 58 and 59 in the circuit of the winding 51. The conductor 54 is preferably sealed in position in the bushing 53, as by being molded in the material thereof or by being surrounded by a sleeve 60 of rubber compound or other suitable material.

The condenser-bushing structure 6 comprises an inner condenser member 64, a metal-cylinder supporting member 65, a collar member 67, a plurality of outer porcelain protective shells 68 and a top terminal structure 70.

The condenser member 64 is preferably constructed of alternate layers of metal foil and hard, molded, fibrous, insulating material, such as paper impregnated with a phenolic condensation product, and is tapered or stepped, for considerable portions of its length, from the ends of a uniform cylindrical mid-portion 71 to its outer extremities. This construction ensures a uniform voltage gradient between the cable 48 and the cover member 2 and prevents undue concentration of electrostatic stresses.

The supporting cylinder 65 is sealed to the mid portion 71 by a sealing medium 73 and, similarly to the metal well section 12, embodies an annular outwardly-extending flange 74 and a combined positioning and strengthening rib 75. It, also, embodies a sloping upper surface 77 and is sealed and secured in position on the flange 32 by a gasket 76 and screws 79, respectively, the latter of which extend into the well cover 15.

The collar member 67 embodies a longitudinal cylindrical portion 80, a sloping under surface 82 for cooperation with the sealing gasket 78 and the sloping upper surface 77, and a laterally-outwardly-projecting annular flange 85, for securing the collar member 67 to the bushing-supporting member 65, by means of bolts 86 which extend between the flanges 74 and 85.

The porcelain shells 68 have portions that are nested and cemented in position, one within another, in a usual manner. A flange 87, of the bottom shell 68, rests on a sealing gasket 88 on a shoulder 89 in the collar 67 and is secured in position in the cylindrical portion 80, by a body of cement 90. The upper shells 68 are smaller than the lower shells, by reason of the tapered upper end (not shown) of the condenser bushing member 64, and an insulating filling compound 92 is disposed between the shells 67 and the condenser member 64.

The stop terminal structure 70 comprises a collar member 94 that is secured to the top shell 68, as by cementing and a member 95 having a lateral lower flange 96 by which it is secured to the collar 94 by means of screws 97.

The member 95 further comprises lifting-
hook portions 99 and a terminal clip 100.

After placing the well structure in the opening 7, the stud 46, at the lower end thereof, may be moved laterally, to adjust the stationary contact member thereof relative to the movable element of the interrupter, as above mentioned, by shifting the flange 18 on the flange 9, as in a ball-and-socket joint.

Since the distance from the stud 46 to the flange 9 is relatively great, a very slight movement of the well structure, to change the angular position of the longitudinal axis thereof, effects a relatively great adjustment of the stud 46. Slight adjustments of the latter are, therefore, almost imperceptible at the parts 9 and 18.

When it is desired to ship the entire structure, the condenser bushing 6, with its appurtenant permanently attached parts, such as the condenser member 64, the supporting cylinder 65, the collar 67, the shells 68 and the top terminal structure 70 may be easily detached by removing the screws 79.

In effecting the above detachment, the cable 48 is also detached from the top terminal structure 70 and allowed to fall into the well 4, when the bushing is removed. This feature is provided because the lower end of the cable must be securely fastened and is not so accessible in the field where its top connection may easily be made.

Thus, the condenser bushing, with its attending parts, as one unit, and the well structure with the cable 48 and the remaining interrupter parts as another unit, may conveniently be separately shipped for reassembly in the field without adjustment and difficult connections. At the place of installation, the outer end of the slackened cable 48 is removed from the well, the interrupter casing and the well are supplied with oil, the cable is threaded through the condenser member 64 and secured to the terminal 70 and the well cover 15 is placed in position, all of which operations may easily and con-

veniently be performed outside the interrupter casing.

Since, as above described, the well structure 4 is thoroughly sealed, the oil in the well and the oil in the interrupter casing, the levels of which are represented by lines *x* and *y*, respectively, are effectively separated.

Thus, when carbon and metallic particles are given off by the interrupter contact members when the latter are operated under heavy 10 loads, and are suspended in the casing oil, the oil in the well is maintained free thereof. This feature is important because any reduction of the insulating value of the oil along the tapered or stepped lower portion of the 15 condenser member 64, might result in breakdown of the bushing and damage to or destruction of the same and surrounding parts.

Further, since a space for gas must be 20 maintained above the main body of oil *Y* in the interrupter, the well structure 4 permits a higher level of the oil *X* therein to be employed, thus providing a more effective protection of the condenser element 64 than if 25 the well were not employed.

In the modification of my invention illustrated in Fig. 2, in which corresponding parts are designated by corresponding reference characters, the construction is substantially the same as that above described, except that the well structure 4 instead of being 30 removably and adjustably mounted on the cover member 2, is permanently fixed thereto, as by welding or brazing the metal section 12 thereof to the cover member.

This construction prevents adjusting the stud 46, at the bottom of the well, in the manner above described, but is a feature of economy over the other construction.

Other slight differences in this form of my 35 invention are that the flange 20, between the metal section 12 and the insulating section 14 of the well, is a separate element, secured to the metal section by screws 102, and the screws 34 extend into the cover member 2, instead of into the well section 12.

While I have shown and described particular forms of my invention, changes may be effected therein without departing from the spirit and scope thereof, as set forth in the appended claims.

I claim as my invention:

1. A high-voltage structure comprising a wall member having a bushing opening therethrough, a casing of substantially cup-shape embodying an insulating portion and disposed locally about the bushing with its open-end perimeter secured to the wall member around said opening, a complete bushing unit having a portion in said casing and conducting means extending through the bushing and the casing.

2. A high-voltage structure comprising a wall member having a bushing opening therethrough, a casing of substantially cup-

shape embodying insulating and metal sections and disposed locally about the bushing with its open end adjacent to the wall opposite said opening, said casing being supported solely by said wall member, a complete 70 bushing unit having a portion in said casing, and conducting means extending through the bushing and the casing.

3. A high-voltage structure comprising a wall member having an opening therethrough, a local bushing well structure sealed to said wall member opposite said opening and including a cover member, and a bushing extending through said cover member in sealed relation thereto at a position adjacent 80 thereto.

4. A high-voltage structure comprising a wall member having a bushing opening therethrough and an annular flange projecting substantially normal to the wall around the opening, and means for receiving a portion of a complete bushing unit including a local bushing well structure having a bottom portion insertable through said opening and a laterally-extending outer flange disposed on said first 90 flange in sealed relations thereto.

5. A high-voltage structure comprising a wall member having a bushing opening therethrough and a sloping seat portion around the opening and a local bushing well structure 95 that is independent of a complete bushing structure which it is to receive and is disposed opposite said opening with a portion cooperating with said sloping seat portion for angularly adjusting the well structure relative to the wall member prior to the reception of the bushing structure.

6. A high-voltage structure comprising a wall member having a bushing opening therethrough and an annular flange projecting substantially normal to the wall around the opening embodying an inwardly-sloping seat portion, and a local bushing well structure having a bottom portion insertable through 105 said opening and a laterally-projecting outer flange cooperating with said seat portion for resting the well structure on the wall member and angularly adjusting the well relative to the wall, said well structure being adapted for the reception of a portion of an independent 110 and complete bushing-unit structure.

7. A high-voltage structure comprising a wall member having a bushing opening therethrough, a local bushing well structure for the reception of a portion of a complete bushing unit and secured to the wall member opposite said opening and including means for conducting current through the wall of the well, and means for adjusting said conducting means relative to a device outside the well 115 with which it is to cooperate.

8. A high-voltage structure comprising a wall member having a bushing opening therethrough, a local bushing well structure for the reception of a complete bushing unit and se- 120

cured to the wall member opposite said opening, means at the bottom of the well for conducting current through the wall thereof including a conductor projecting from the bottom of the well, and means for adjusting said conductor angularly relative to the axis of said opening.

9. A high-voltage bushing structure comprising a wall member having a bushing opening therethrough, a local bushing well structure secured to the wall opposite said opening, means for conducting current through the bottom of the well including a conductor for extension along the axis of the well therein, and a complete bushing unit for insertion in the well over said conductor.

10. A high-voltage bushing structure comprising a wall member having a bushing opening therethrough, a local bushing well structure secured to the wall opposite said opening, means for conducting current through the bottom of the well including a flexible conductor in the well, and a bushing for insertion in the well and having a central opening for the reception of said flexible conductor.

11. A high-voltage structure comprising a wall member having a bushing opening therethrough, a local bushing well structure secured to the wall opposite said opening, a complete bushing unit having a portion in the well, a transformer element disposed around said portion and a conducting lead for said element extending through the wall of the well in sealed relation thereto.

12. A high-voltage structure comprising a fluid-containing casing including a metal cover member having an opening therethrough, a well structure comprising an upper metal section sealed to the cover member around said opening, a bottom insulating section sealed to said upper section, a lid member for the well structure having an opening therethrough, and a complete condenser bushing unit supported in the opening in said lid member in sealed relation thereto adjacent thereto.

13. A high-voltage structure comprising a fluid-containing casing including a metal cover member having an opening therethrough, a well structure comprising an upper metal section sealed to the cover member around said opening, a bottom insulating section sealed to said upper section, and having downwardly converging side walls, a lid member for the well structure having an opening therethrough, and a complete condenser bushing unit supported in the opening in said lid member in sealed relation thereto adjacent thereto, said bushing having a portion of substantially uniform relatively small diameter extending through said upper metal section and a tapered lower end portion in said bottom insulating section.

14. A high-voltage structure comprising a fluid-containing casing including a metal cov-

er member having an opening therethrough, a well structure comprising an upper metal section sealed to the cover member around said opening, a bottom insulating section sealed to said upper section, a lid member for the well structure having an opening therethrough, a complete condenser bushing unit extending through the opening in the lid member and means on the bushing for supporting the same, and sealing the same to, said lid member.

15. In combination, a wall member having a bushing opening therethrough, a bushing shield of substantially cup-shape extending transversely to said wall with its open end opposite said bushing opening, a complete bushing unit having a portion for disposition in said shield, and means for supporting the shield and providing for the removal of said unit while said shield remains in place.

16. In combination, a well member having a bushing opening therethrough, a bushing shield of substantially cup-shape extending transversely to said wall with its open end opposite said bushing opening, a complete bushing unit having a portion for disposition in said shield, and means for adjustably securing said shield in position and providing for the removal of said unit while said shield remains in place.

17. In combination, a wall member having a bushing opening therethrough, a bushing shield of substantially cup-shape extending transversely to said wall with its open end opposite said bushing opening, a complete bushing unit disposed partially inside and partially outside said shield, and means for closing said open end and supporting the bushing unit.

18. In combination in a high-voltage circuit-interrupting device, a casing having a bushing opening, and an insulating element of substantially cup-shape disposed in the casing opposite said opening independent of the bushing for receiving the bushing and supporting a contact member, said element constituting a shield for receiving oil and maintaining it separate from oil in the casing.

19. In combination, a wall member having an opening therethrough, a shield of substantially cup-shape extending transversely to said wall with its open end secured thereto in position adjacent to, and in register with, said opening, and a complete bushing unit removably secured in position independently of the shield with a portion in said shield and a portion projecting from the opposite side of said wall at which the bushing is disposed.

20. In combination, a wall member having an opening therethrough, a shield of substantially cup-shape extending transversely to said wall opposite said opening and having a laterally outwardly projecting portion removably secured to said wall at the side of the latter opposite to which the major portion of the shield is disposed, and a complete

bushing unit removably secured in position with a portion in said shield and a portion projecting therefrom.

21. In combination, in a high-voltage structure, a vessel for containing a fluid-immersed electrical device, a complete bushing unit extending through a wall of the vessel, and means supported independently of said unit for segregating said fluid from a fluid surrounding a portion of the bushing unit and providing for the removal of said unit while said segregating means remains in place.

22. In combination, a wall member having an opening therethrough, a shield of substantially cup-shape extending transversely to said wall with its open end in register with said opening and having a laterally-extending portion adjacent to the wall for attachment thereto, and a complete bushing unit removably secured in position with a portion in said shield and a portion projecting therefrom.

23. In combination, a wall member having an opening therethrough, a shield of substantially cup-shape of smaller diameter than said opening extending transversely to said wall with its open end in register with said opening and having laterally-extending portions adjacent to the wall for attachment thereto, and a complete bushing unit removably secured in position with a portion in said shield and a portion projecting therefrom.

In testimony whereof, I have hereunto subscribed my name this 10th day of May, 1927.
